UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

CARBON-CONSUMING MEANS FOR COKE OVENS.

1,410,783.

Specification of Letters Patent. Patented Mar. 28, 1922.

Application filed January 5, 1920. Serial No. 349,577.

To all whom it may concern:

Be it known that I, JOSEPH VAN ACKEREN, a citizen of the United States, residing in Pittsburgh, in the county of Allegheny and State of Pennsylvania, have invented a new and useful Improvement in Carbon-Consuming Means for Coke Ovens, of which the following is a specification.

This invention relates to coke ovens, more particularly to coke ovens of the by-product type, and has for its primary object to provide a novel and highly efficient means for burning out the carbon deposits that accumulate in the gas passages and nozzles which supply fuel gas to the heating flues contiguous to the coking chambers of the plant.

With the above object and other objects in view, such as are found to obtain in the improvements in construction and operation hereinafter set forth, the invention consists in certain novel constructions, arrangements, and combination of parts and instrumentalities pointed out in the claims at the end of the specification.

In the accompanying drawings, forming a part of this specification, and showing, for purposes of exemplification, a preferred form and manner in which the invention may be embodied and practiced, but without limiting the claimed invention specifically to such illustrative instance or instances:—

Figure 1 is a fragmentary side elevational view of a coking plant of the by-product type, equipped with improvements constructed in accordance with the present invention.

Figure 2 is a vertical sectional elevation of the same, taken substantially in a plane indicated by the line 2—2 of Figure 1.

Figure 3 is an enlarged side sectional elevation of the construction illustrated in Figures 1 and 2.

Figure 4 is an enlarged vertical sectional elevation taken substantially in the same plane as Figure 2.

Figure 5 is an enlarged side sectional elevation similar to Figure 3, but illustrating a modified construction.

Figure 6 is a vertical sectional elevation taken in a plane indicated by the line 6—6 of Figure 5.

Like characters of reference designate like parts throughout the several views.

55 In its present embodiment, the invention

is incorporated in a coking plant of the well known Koppers cross regenerative type, exemplified in the patent to H. Koppers No. 818,033, dated April 17, 1906, and other Koppers patents. For convenience the present description will be confined to this embodiment and use of the invention; it will be understood, however, that the invention is readily susceptible of other valuable applications and that its scope is by no means confined to the specific use and specific embodiment herein described as an illustrative example.

The well known Koppers cross regenerative by-product coking plant embodies in its construction a plurality of the usual cross-wise extending coking chambers which alternate with cross-wise extending heating walls, each heating wall 21 being provided with a plurality of heating flues or vertical flame flues 22, as indicated in Figure 2. Beneath the heating walls 21 and parallel therewith are the usual cross regenerators indicated diagrammatically at 23 in Figure 1, there being the usual arrangement of a pair of such cross regenerators companion to each cross-wise extending heating wall 21. The regenerators communicate with the heating flues of their companion heating walls by means of the usual short ducts or ports and function to take up the heat of the gases outflowing from the heating flues of the aforesaid heating walls and impart such heat to the outside air in-flowing through the regenerators to the heating flues to augment the flame temperature of the gas burning in the heating flues in which combustion is taking place.

The inlets to the heating flues or flame flues 22 are located at their respective bottoms and at each inlet there is provided a short fuel gas duct 24 equipped with a suitable gas nozzle 25, through which the inflowing fuel gas passes into the heating flues. Extending cross-wise from the opposite sides of the coking plant or battery are gas channels 26, there being a pair of such channels arranged approximately end to end for each heating wall. The several heating flues of each heating wall are connected at their top outlets by a common out-flow channel; the gas ducts 24, however, of a number of the heating flues of a heating wall lead from one member of the pair of companion gas channels 26, whereas the gas ducts 24 of the

heating flues on the opposite side of the coke oven battery lead from the other member of said gas channels 26. Communicating with the inlets of the gas channels on the opposite sides of the coke oven battery are gas-guns 27; the series of gas-guns 27 on each side of the battery are supplied with gas from the usual gas main extending longitudinally along each side of the battery.

10 In the operation of a coke oven battery of the type above specified, the several heating flues along one side of the battery are supplied with fuel gas and combustion supporting air for a period of time determined by the necessity of practical operation, while the fuel gas and air is shut off from the several heating flues along the opposite side of the battery. The products of combustion pass out of the ignited heating flues 15 into the out-flow channels above them and thence flow downwardly through the heating flues on the opposite side of the coke oven battery, on which the supply of gas and air is cut off. At the end of a period of 20 operation in this manner, a reversal takes place and the supply of gas and air is shut off from the previously ignited heating flues on one side of the battery and concurrently such supply is permitted to flow into the 25 heating flues along the opposite side of the battery, that previously functioned as out-flow passages for the exhaust gases. Thus, the heating flues along each side of the battery function alternately as combustion 30 chambers and as exhaust gas flues. Suitable means is provided in coking plants of the type herein described for opening up the supply of fuel to the series of gas-guns of one side of the battery and for concurrently 35 cutting off the supply from the series of gas-guns on the opposite side of the battery at the time of reversal, said means being of the usual type operable from a central station and adapted to control all of the gas-guns simultaneously.

40 The several cross regenerators extending inwardly along each side of the battery function alternately, as stated above, to take up the heat from the out-flowing exhaust gases and to impart such heat to the inflowing air. Provision is made for alternately establishing communication between the several regenerators and an air supply and for establishing communication between such regenerators and a stack or other suitable exhaust through which the spent gases may pass into the atmosphere. The reversal of flow through the regenerators takes place concurrently with the reversal 45 of fuel supply to the heating chambers hereinabove set forth, and the air supply is connected with those regenerators leading to the ignited heating flues, whereas the stack or exhaust is connected with the regenerators 50 along the opposite side of the battery and

receiving the out-flow of exhaust gases from the out-flow operating heating flues. It will be understood that the regenerators are of the usual construction comprising bay shaped chambers filled with checker brick. 70

Communicating with each regenerator is an air box 28; in the arrangement shown the air boxes of the several regenerators are located in rows disposed on opposite sides of the coke oven battery. Each air box is conveniently in the form of a receptacle supported beyond the side wall of the coke oven battery and having three main ports: a port 29 opening into its companion regenerator, a port 30 opening into the outer air and a port 31 opening into the usual stack conduit. A lid 32 is provided for opening and closing the air port 30 of each air box and said lid is mounted on the arm 33 of a bell crank pivoted at 34 on a bracket 35 secured to the air box. The arms 36 of the bell cranks of the several air boxes on each side of the battery are pivoted at their upper end to sleeves 37 carried by the reversing cables 38, there being such a cable extending along each side 80 of the battery. On movement of the cable in one direction the bell cranks of the several air boxes on the same side of the battery are operated to open the lids 32 and thereby to admit air into the air boxes and their connected regenerators. Such opening movement of the lids of the air boxes on one side of the battery is accompanied by a concurrent movement of the reversing cable on the 85 opposite side of the battery, but in the opposite direction to close the lids of the several air boxes which it controls. The coking plant is equipped with suitable mechanism for opening and closing the stack conduits 90 communicating with the series of air boxes on the opposite sides of the battery. In the operation of the plant, the opening of a stack conduit takes place concurrently with the closing of the air ports of the several air boxes with which such stack conduit is connected, so that the operation of reversal by 95 movement of the above described reversing cable has the effect of placing all the air boxes on one side of the battery in communication with the outer air and out of communication with the stack, and all the air boxes on the opposite sides of the battery in communication with the stack and closed to the outer air. Pivotaly mounted within each air box is the usual butterfly valve 39 mounted on a 100 shaft 40 and provided with the usual adjusting segment 41. The butterfly valve of the several air boxes are adjusted by operation of their segments 41 in the usual way to regulate the draft through the regenerators 105 to the stack. 110

115 The above is a brief outline of the construction and mode of operation of a coke oven battery of the well known Koppers cross regenerator type. It will be understood that 120 125 130

the reversal of flow through the regenerators takes place concurrently with the reversal of feed of fuel gas to the heating flues, and that the control of such reversal may be effected 5 from a central station in the usual way.

The present invention relates to an improved and efficient means for burning out the deposited carbon that accumulates in the fuel gas nozzles and gas supply passages of 10 the several heating flues during the ignition period and utilizes a proportion of the exhaust gas to burn out this carbon. The exhaust gas passing through the heating flues, when operating as out-flow passages contains 15 a sufficient percentage of a medium such as air to unite with the carbon that has accumulated in the nozzles and gas passages during the previous period of ignition. By utilizing hot exhaust gas to burn out the carbon 20 the tedious and difficult manual operation of cleaning the nozzles and gas passages, which would otherwise become clogged, is entirely eliminated. Furthermore, the carbon removing operation is effected without 25 any interruption in the operation of the oven whatsoever and without any appreciable loss of heat.

Communicating with each fuel gas supply channel 26 is an exhaust gas passage 30 42 formed in each pillar wall 43 between a pair of adjacent regenerators. In accordance with the invention a proportion of the exhaust gas from the several heating flues communicating with each gas channel 35 26 is adapted to pass out through the several channels 42 when said heating flues are being operated as out-flow passages for the exhaust gas. This results in causing the exhaust gas to pass through the gas ducts 24, nozzles 25, 40 and gas channels 26 of the out-flow operating heating flues and in so doing the hot exhaust gas unites with and burns out the carbon that has accumulated in the ducts, nozzles and channels.

45 In order to provide a sufficient draught for effecting the passage of the exhaust gases through the exhaust gas passages 42 controlled-valve means is provided for establishing communication between said passages 42 and the several air boxes 28 when the latter are in communication with the stack conduit. There are a plurality of exhaust gas passages 42 on each side of the coke oven companion respectively to the individual air boxes of the two opposite series of air boxes.

50 Referring now to the form of the invention illustrated in Figures 1 to 4 inclusive; the discharge ends of the exhaust gas passages 42 communicate with the inner open 60 ends of exhaust gas guns 44 respectively supported by the pairs of vertical buck stays 45 mounted in front of the pillar walls and having their inner ends projected into the enlarged discharge ends of the exhaust gas 65 passages, as shown more particularly in

Figure 4. The outer ends of the respective exhaust gas guns 44 are closed by removable covers 46. Adjacent the outer end of each exhaust gun is formed a depending valve casing 47 within which projects a vertically 70 slideable valve stem 48 having a head 49 adapted to seat over the upper end of the valve casing 47 to prevent the passage of gas through the valve casing when the valve is closed. Beneath the head 49 the valve 75 stem 48 is channelled, as shown at 50, to permit the passage of exhaust gas through the valve casing when the valve is open. The valve stems 48 of the several exhaust gas guns 44 project through bearings 51 80 formed in the top thereof and are provided with vertically extending slots 52.

According to the invention, the control of the operation of the valve in the exhaust gas guns is effected simultaneously with the reversal of direction of flow through the regenerators and by the same power connections. Pivoted at one end to each of the collars 37 on the air reversing cable 38 are links 53, the other ends of which are respectively pivoted to the arms 54 of bell crank levers pivoted at 55 on the several exhaust gas guns. The other arms 56 of said bell crank levers are adapted respectively to enter the slots 52 of the companion valve stems 90 48 and are provided with rollers 57 respectively adapted to engage the top and bottom faces of said slots, as shown in Figure 3. With this construction on movement of the reversing cable toward the right, as indicated 100 by dotted lines in Figure 3, the motion of the cable is transmitted through the several links and bell cranks 54 to shift the valve stems 48 downwardly and engage the valve heads 49 on the seats at the upper end of 105 the valve casings, thereby closing the valves. The valve closing movement takes place concurrently with the movement of the reversing cable 38 to open the lids 32 of the air boxes. The movement of the reversing cable 100 38 to close the lids of the air boxes, through the connections hereinabove described operates to lift the valve heads off their seats and open up the valve casings to the several exhaust gas guns. Pipings 58 provided with 115 manually operable control valves 59 connect the respective valve casings 47 with the air boxes 28. When the valves are open the exhaust gases pass through said pipings to the several air boxes and thence flow out to the 120 stack. The flow may be controlled by adjusting the valves 59.

125 In the modified form of the invention illustrated in Figures 5 and 6, the principle of operation is substantially the same as that which has been hereinbefore described. Pipes 60, however, connect the exhaust gas guns 44 with valve casings 61 which are in turn connected by pipes 62 with the several air boxes. The manually adjustable 130

control valves 63 are incorporated in the first mentioned pipes 60. Formed in each valve casing 61 is a seat 64 having a central discharge outlet 65. Pivoted on an arm 5 fixed on a shaft 67 is a valve head 68 adapted to be raised and lowered with respect to the valve seat 64 to open and close the discharge outlet 65. The opening and closing of the valves 68 of the several valve 10 casings 61 is controlled by links 69 respectively mounted on the shafts 67 and having pivotal connections in slotted links 70 pivoted on the collars 37 carried by the air reversing cable 38. These link connections 15 transmit the lid-opening movement of the cable 38 to the several valves 68 to close the same, and the reverse movement of said cable to said valves to open the same.

In both forms of the invention illustrated 20 in the drawings, the pipe connections leading from the valves 47 and 61 of the exhaust gas passages 42, are connected with the respective air boxes beneath the pivotal axis of the butterfly valves 39 within said 25 air boxes in order to secure the full stack pull on the relatively indirect and tortuous exhaust gas passages of the de-carbonizing means. The suction through the exhaust gas passages 42 may be adjusted by manipulation of the valves 59 or 63, as the passages 30 42 are beyond the draft regulation afforded by adjustment of the butterfly valves 39. Thus the draft control through the exhaust passages 42 is entirely independent and beyond the draft control through the regenerators. In practice, it will be found desirable 35 to manipulate the adjusting valves 59 or 63, in such manner that the adjusting valves nearest to the stack are more nearly closed than those farthest from the stack, and such 40 an adjustment of the valves will insure the proper distribution of the draft in the several exhaust gas passages of the oven battery.

45 The invention as hereinabove set forth is embodied in a particular form of construction, but may be variously embodied within the scope of the claims hereinafter made.

What is claimed is:

50 1. In a coke oven having coking chambers, heating flues contiguous thereto operable alternately for in-flow and for out-flow, regenerators communicably connected with said heating flues, fuel-gas supply passages and nozzles communicating with the inlets of said heating flues and devices for periodically reversing the direction of flow through the regenerators and flues, combined with the improvement characterized 55 by exhaust passages leading directly from said flues independently of the regenerators, and controlled-valve means operatively connected with said exhaust passages for permitting a portion of the out-flow from the flues to pass through the fuel-gas passages 60

and nozzles and through said exhaust passages, to consume carbon deposited in said gas passages and said nozzles during the previous burning operation; substantially as specified. 70

2. In a coke oven having coking chambers, heating flues contiguous thereto operable alternately for in-flow and for out-flow, regenerators communicably connected with said heating flues, fuel-gas supply passages communicating with the inlets of said heating flues, and devices for periodically reversing the direction of flow through the regenerators and flues, combined with the improvement characterized by exhaust passages leading directly from said flues independently of the regenerators, and control-valve means operatively connected with said exhaust passages for permitting a portion of the out-flow from the flues to pass directly through the fuel-gas passages and be drawn through said exhaust passages, to consume carbon deposited in said fuel-gas 75 80 passages during the previous burning operation; substantially as specified. 85

3. In a coke oven having coking chambers, heating flues contiguous thereto operable alternately for in-flow and for out-flow, regenerators communicably connected with said heating flues, fuel-gas supply passages 90 communicating with the inlets of said heating flues and devices for periodically reversing the direction of flow through the regenerators and flues, combined with the improvement characterized by means for withdrawing a portion of the out-flow from the flues directly through said fuel-gas passages and independently of the flow through the regenerators, to consume carbon deposited in said gas passages during the previous 95 burning operation; substantially as specified. 100

4. In a coke oven, in combination: coking chambers; heating flues contiguous thereto operable alternately for in-flow and for out-flow; regenerators communicating with said heating flues and adapted to be operated in alternation to take up the heat of the out-flow and impart it to the in-flow; combustible-gas supply passages communicating with the inlets of said heating flues; reversible valve means for permitting a feed of gas to the gas supply passages of the in-flow operating heating flues and for concurrently shutting off the gas feed from the passages of the out-flow operating heating flues; air boxes connected with said regenerators; a stack for the out-flow, communicating with said air boxes; means for reversing the flow through said regenerators, embodying, valve 110 connections for permitting the outer air to flow into the air boxes and regenerators connected with the in-flow operating heating flues and for concurrently connecting with the stack the air boxes and regenerators 115 120 125 130

nected with the out-flow operating heating flues; exhaust-gas passages adapted to connect the gas passages directly with said air boxes; and valve means interposed between 5 said exhaust passages and the air boxes, and operable conjointly with the reverse of flow through the regenerators, for permitting a portion of the out-flow to pass through the 10 gas passages directly to the air boxes, to consume carbon deposited in said gas passages during the previous burning operation; substantially as specified.

5. In a coke oven having coking chambers, heating flues contiguous thereto operable alternately for in-flow and out-flow, regenerators communicably connected with said heating flues, fuel-gas supply passages communicating with the inlets of said heating flues, and devices for periodically reversing the 15 direction of flow through the regenerators and flues, combined with the improvement characterized by means operable conjointly with said reversing devices for withdrawing a portion of the out-flow from the flues directly 20 through said fuel-gas passages and independently of the flow through the regenerators, to consume carbon deposited in said fuel-gas passages during the previous burning 25 operation; substantially as specified.

30 6. In a coke oven in combination: coking chambers; heating flues contiguous thereto operable alternately for in-flow and for out-flow; regenerators communicating with said heating flues and adapted to be operated in alternation to take up the heat of the out-flow and impart it to the in-flow; combustible-gas supply passages and nozzles communicating with the inlets of said heating flues; reversible valve means for permitting a feed 35 of gas to the gas supply passages and nozzles of the in-flow operating heating flues and for concurrently shutting off the gas feed from the passages and nozzles of the out-flow operating heating flues; an air supply connected with said regenerators; a stack for

the out-flow also connected with said regenerators; means for reversing the flow through said regenerators; and means, operable conjointly with the reversal of flow through the regenerators, for permitting a 50 portion of the out-flow to pass from the gas passages and nozzles directly to the stack connection with the out-flow operating regenerators, to consume carbon deposited in said gas passages and nozzles during the 55 previous burning operation; substantially as specified.

7. In a coke oven, in combination: regenerators; heating flues; fuel passages communicating with the heating flues independently 60 of the regenerators; and means for admitting exhaust gas from said heating flues directly into said fuel passages to consume carbon deposited therein; substantially as specified.

8. In a coke oven battery, the combination with the heating flues, the fuel passages communicating with said heating flues, the regenerators communicably connected with said heating flues independently of said fuel 70 passages, and means for reversing the burning operation of said battery, of means for admitting exhaust gas from the heating flues into said fuel passages to consume carbon deposited therein; substantially as specified. 75

9. In a coke oven battery, the combination with the heating flues, the fuel passages communicating with said heating flues, the regenerators communicably connected with said heating flues independently of said fuel 80 passages, and means for reversing the burning operation of said battery, of means for admitting exhaust gas from the heating flues into said fuel passages to consume carbon deposited therein, and means for opening 85 such exhaust gas supply to the fuel passages on one side of the battery when the fuel-supply is shut off on the same side; substantially as specified.

JOSEPH VAN ACKEREN.
